REFACING TOOL FOR CRANKSHAFT JOURNALS

Ernest Aubrey Vester, Danville, Ill., assignor of
one-fourth to Harry W. Reuther, Danville, Ill.

Application April 22, 1944, Serial No. 532,303

2 Claims. (Cl. 82—4)

My invention relates to improvements in refacing tools for use in reconditioning the main journals of crankshafts of automobile engines.

The invention is designed with the primary object in view of providing a simply constructed, easily operated device of few parts adapted for resurfacing the main journals of automobile engine crankshafts and turning the same down to a new size, all without removing the crankshaft from the engine, and which is easy to apply, may be finely adjusted and manufactured for the trade at a comparatively low cost as a garage or kit tool.

Other and subordinate objects are also comprehended by my invention, all of which, together with the precise nature of my improvements, will be readily understood when the succeeding description and claims are read with reference to the drawings accompanying and forming part of this specification.

I said drawings:

Figure 1 is a view in bottom plan of my improved refacing tool.

Figure 2 is a view in longitudinal section illustrating the tool applied.

Figure 3 is a view in transverse section taken on the line 3—3 of Figure 1.

Figure 4 is a view in perspective of the cutting blade.

Figure 5 is a disassembled view in perspective of the guide plate and the guide bars at one side of the plate.

Referring to the drawings by numerals, my improved refacing tool, in the preferred embodiment illustrated, comprises, as its basic element, a flat guide plate 1 of elongated rectangular form, of any suitable metal, provided at what constitutes the front end thereof with an upstanding edge lip 2 extending across the plate and for a purpose to be explained.

An elongated, rectangular, plate-like, cutting blade holder 3 is slidably opposed to the bottom face of the guide plate 1 for endwise adjustment forwardly and rearwardly thereof. The blade holder 3 is provided with a thickened front end portion 4 for reinforcing purposes, a transversely rounded front end 5 provided with an upwardly and forwardly inclined square slot 6 extending from side to side of said holder, a pair of longitudinally extending slots 7 in the portion 4 adjacent opposite sides of the holder 3, and a pair of similar slots 8 in its longitudinal center and in the rear of the portion 4 suitably spaced apart longitudinally of the holder for a purpose presently apparent.

The blade holder 3 is mounted on the guide plate 1 by means of a pair of threaded studs 9 depending from said guide plate 1 through the slots 8 with nuts 10 and washers 11 thereon for tightening against said holder 3 and clamping the holder to the guide plate 1 in different set positions of said holder. The studs 9 are provided with rivet head shanks 12 by means of which said studs are secured in the guide plate 1, and below the nuts 10, with eye-forming ends 13 presently again referred to.

A pair of front guide bars 14 secured to opposite sides of the guide plate 1, by screws 15, to overlap the sides of the blade holder 3, guide said holder 3 at its front end and prevent side play of said holder during adjustment of the latter. A second pair of longer guide bars 16 secured to opposite sides of the guide plate 1 in the same manner as the guide bars 14 in the rear of the bars 14 guide the blade holder 3 additionally, intermediate its ends, when said holder is being adjusted.

For adjusting the blade holder 3, an adjusting shaft 17 is provided beneath said holder with a rear end portion thereof rotatably mounted in a suitable bracket 18 depending from the rear end of said holder 3 and secured thereto, as by screws 19, said shaft 17 being restrained against endwise movement in the bracket 18 by means of a pair of collars 20 fixed on said shaft by pins 21 upon opposite sides of said bracket 18. The front end portion of the adjusting shaft 17 is rotatably and slidably mounted in a bushing 22 fitted in the eye-forming end 13 of the foremost stud 9 and retained in said end by end flanges 23 on the bushing. A portion of the adjusting shaft 17 in the rear of the bracket 18 is formed with a wrench hold 24 and an intermediate portion 25 of said shaft is threaded in the eye-forming end 13 of the rear stud 9. Thus, as will be seen, by applying a wrench, or other tool, to the wrench hold 24, the nuts 10 being loosened, the adjusting shaft 17 may be rotated in opposite directions to feed the same forwardly or rearwardly in the end 13 of the stud 9 and thereby correspondingly adjust the blade holder 3 at will.

A suitable cutting blade 26 for turning down a main crankshaft bearing is secured in the slot 6 to extend out of the same with an upward and forward inclination, by means of set screws 27 extending obliquely upwardly in the front end 5 of the blade holder 3. As will be understood, the blade 26 is designed to extend along the entire length of the main bearing and is provided with

a suitable cutting edge 28 extending throughout the length of said blade.

Referring now to the use and operation of the invention, after the lower bearing cap section, not shown, of the main journal to be refaced has been detached, the described tool is attached at its front end to the bottom face of the usual web 29 for the main bearing, at one side of the main journal 30 and by means of a pair of the usual stud bolts 31 for the cap bearing section. For this purpose, the guide plate 1 is provided adjacent its front end with a pair of suitably spaced stud-receiving openings 32 aligned with the slots 7 and said plate with the studs 31 extending through the openings 32 and said slots 7 is clamped against the web 29 by means of the usual castellated nuts 33 on said studs 31. The lip 2 is inserted in the bearing seat or opening 35 against the usual upper liner section 34 to prevent said liner section from creeping around during the refacing operation. In the described application of the tool, the cutting blade 26 may be adjusted against the main journal 30, as occasion may require, by loosening the nuts 33 and 10 operating the adjusting shaft 17 in the manner already described, and clamping the blade holder 3 in selected adjusted position by means of said nuts. As will be understood, the refacing is accomplished by driving the crankshaft, not shown, so that the main journal is revolved slowly against the cutting edge 28 of the cutting blade 26.

As will now be manifest, the tool of my invention provides for refacing main journals without removing the crankshaft and in applying and operating the tool it is merely necessary to detach the usual pan from the engine and the lower cap journal section, not shown, of the main journal to be refaced and turned down. Thus, substantially all of the many operations heretofore necessary as preliminary to refacing main journals are eliminated, such, for instance, as taking the engine out of the automobile, the crankshaft out of the motor, replacing piston rings, et cetera,

and much time and labor may be saved in the practice of my invention.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. A tool for refacing and turning down shaft journals of automobile engines comprising a guide plate, a blade holder of plate-like form having a front end provided with a cutting blade mounted therein for positioning against a journal, means to attach said plate to the bottom face of the bearing web of a journal to be refaced, means to mount said holder on said plate for adjustment into different set positions to variably position said blade relative to said journal, and means to adjust said holder, said guide plate having a right angled edge lip for positioning in the bearing seat to prevent a bearing liner from interfering with said blade.

2. A tool for refacing and turning down shaft journals of automobile engines comprising a guide plate, a blade holder of plate-like form having a front end provided with a cutting blade mounted therein for positioning against a journal, means to attach said plate to the bottom face of the journal web of a journal to be refaced, means to mount said holder on said plate for adjustment into different set positions to variably position said blade relative to said journal, and means to adjust said holder, the means last mentioned comprising studs depending from said plate, said holder having slots therein through which the studs extend, and an adjusting shaft rotatably mounted on said holder, said shaft being threaded through one stud and slidably and rotatably mounted in another stud.

ERNEST AUBREY VESTER.
